ELECTRON DISCHARGE DEVICE

Maximiliaan J. O. Strutt and Petrus H. J. A. Kleynen, Eindhoven, Netherlands, assignors, by mesne assignments, to Radio Corporation of America, New York, N. Y., a corporation of Delaware

Application November 24, 1937, Serial No. 176,174
In Germany November 26, 1936

6 Claims. (Cl. 250—27.5)

This invention relates to a device comprising an electric discharge tube having a cathode, an anode and two or more other electrodes, one of which consists only of a few rods or slat portions, and in which the electrons emitted by the cathode are united into beams, the grid-voltage anode current characteristic curve being determined by influencing the dimensions of the beam.

The principal object of the invention is to provide an electron discharge device which can be built easily and in a comparatively simple manner to have the desired characteristic curve.

In accordance with the present invention, the electrons issuing from the cathode are concentrated in radial beams by rod or plate-shaped members arranged parallel with the longitudinal axis of the cathode, and means at the ends of the electrode system affect the form of the radial beams in a direction parallel with the longitudinal axis of the cathode. In this way the spot to be cast on the anode can be given any optional form.

In one form of tube constructed according to the present invention an intercepting electrode is mounted in front of and close to the anode, and so shaped that, in combination with the beam-shape, a characteristic curve is obtained having the desired form in a definite case.

The end electrodes which extend in a plane substantially normal to the cathode, may be plate-shaped or sheet electrodes and may be connected to a point of constant potential, for instance to the cathode or to another point of constant or negative potential or to a variable voltage, so that variations of the voltage affect the electrostatic field due to the end electrodes and cause a variation in the width of the beam in a direction parallel with the cathode and consequently in the shape of the beam.

One or more additional grids may be provided between the control grid and the intercepting electrode, one of which additional grids may act as a protective grid, although the functions of the intercepting electrode and of the protective grid may be united in one electrode. The invention may be used with pentodes and octodes wherein an additional pentode suppressor grid is provided between the intercepting electrode and the anode.

The invention will be more clearly understood by reference to the accompanying drawings in which, by way of example, various forms of embodiments of the invention are shown and in which Figures 1 and 2 are longitudinal sections of mounts of tubes embodying the invention, Figure 3 is the form of the anode spot obtained

with tubes constructed as shown in Figures 1 and 2, Figures 4 and 5 are longitudinal sections of other modifications, Figure 6 is a cross-section of Figure 1 along the section line 6—6, Figures 7 and 8 are longitudinal sections of other modifications, Figure 9 shows the anode spot produced by tubes constructed as shown in Figures 7 and 8, Figure 10 shows a mount partly in longitudinal section of still another modification, Figure 11 is the anode spot produced by the tube shown in Figure 10, Figure 12 is a plan view of the screen grid with which a straight characteristic curve can be obtained, Figure 13 is a plan view of a screen grid by which an exponential grid voltage-plate current characteristic curve may be obtained, Figure 14 is a developed view of the anode of the tube shown in Figure 10, and Figure 15 shows the anode spot produced by tubes constructed as in Figures 4 and 5.

In Figures 1 and 2 the mount comprises a press 1, which carries an electrode system comprising a rectilinear cathode 2, preferably of the indirectly heated type, a control grid 3 consisting of rods parallel to the longitudinal axis of the cathode and a tubular anode 4 surrounding and coaxial with the cathode and the control grid. By the effect of the control grid voltage the electron discharge from the cathode to the anode is concentrated or united into electron beams which are flattened and are in general rectilinear in cross-section with the width of the beam extending lengthwise of the cathode. Between the beam forming control grid and the anode is mounted an apertured intercepting electrode or anode 4a with an aperture 4b in the path of the electron beam. The form of the aperture in the intercepting electrode in combination with the shape of the electron beam determines the shape of the anode spot and the shape of the characteristic curve of the tube. The shape of the electron beam formed by the control grid 3 is affected and determined by end members such as the sheet electrodes or discs 5 and the rod electrodes 6 in Figures 1 and 2, which are mounted at the opposite ends of the electrode system so as to extend in planes normal to the cathode. By impressing voltage on these end members 5 and 6 an electrostatic field is produced which will affect the beam shape in a direction parallel with the longitudinal axis of the cathode. Tubes constructed as shown in Figures 1 and 2 will produce an anode spot illustrated in Figure 3 and the form of this spot varies with variation in voltage of the control grid and of the end members. The tube is connected into a circuit as indicated in

Figure 1. An input transformer 20 has connected to one side of its tuned secondary the lead to the control grid 3 and its other side connected to the anode voltage supply 21. The end plates 5 and 5 the end control rods 6 may be connected to the grid side of the secondary of the transformer by means of conductor 22 and adjustable tap 23 or they may be connected directly to the grid lead as indicated by the dotted line. The output is 10 fed to the transformer 24. If desired, the end plates 5 could be connected to the cathode. The intercepting electrode or anode 4a is connected to an intermediate point on the anode voltage supply source. It will be noted that the end rods 6 15 extend normal to the cathode and lie in a median plane of beams produced by control grid 3. This position and the voltages applied to the rods during operation of the tube cause the curved upper and lower edges of the spot shown in Figure 3. 20 In Figures 1 and 2 the end members 5 are shown connected to the control grid end of the secondary of the input transformer and, therefore, vary in potential with variations in control grid voltage. When the control grid voltage is high, the anode 25 spot, as illustrated in Figure 3, has the form or outline 11. As the control grid voltage decreases, the anode spot shrinks to the form 12, and at still lower control grid voltages, shrinks to the form 13.

30 Figures 4 and 5 show a modification in which the end members for affecting the shape of the electron beam in a direction parallel to the cathode are in the form of rods 7 located at opposite ends of the electrode system and by a rigid 35 metal connector 7a to the control grid 3 and carried by it if desired, although they are shown provided with a separate support and lead.

Figure 15 shows the form of the anode spot produced by the tube shown in Figures 4 and 5, 40 the anode spot having the form 11 at high grid voltages and shrinking first to the form 12 and then to the form 13 as the control grid voltage is lowered. The effect of eliminating the end 45 plates 5 is shown in Figure 15 where wider and longer legs appear at the top and bottom of the spot shown in Figure 11. The reason for this is that the beam is compressed only by the field of the rods 7 in the path of the beam, whereas in the construction shown in Figures 1 and 2 both 50 the shields 5 and the end rods 6 exert an influence on the shape of the beam and have a greater compressive action than the rods 7 alone. The construction of the tube shown in Figures 4 and 5 is simpler than that shown in Figures 1 and 2 and in the resulting anode current the 55 difference between maximum and minimum current is greater.

Figures 7 and 8 illustrate a modification in which the end members are sheets or discs 8 at 60 opposite ends of the electrode system, these end members having a separate connection by which any desired voltage may be impressed upon the end members. When the end members are connected to the control grid, the anode spot, as 65 shown in Figure 9, is in general, similar to that obtained from the tubes shown in the preceding figures, the spot having the form 11 at high control grid voltage, and shrinking to the forms 12 and 13 in succession as the control grid voltage 70 is lowered.

Figure 10 is a longitudinal section of a modification in which the sheet or disc end members 8 are similar to those shown in Figure 7; the anodes 9 are in the developed state of the form 75 illustrated in Figure 14 so as to provide two

diametrically opposite slots or apertures in the path of the electron beams from the cathode, and are surrounded by an electrode 10. When the end members 8 of the tube shown in Figure 10 are connected to the cathode, preferably by a connection 8a inside the tube, the anode spot obtained has the form shown in Figure 11. With these connections, the anode spot at high control grid voltage is of the substantially square form 11 and as the grid voltage is lowered, the 10 spot shrinks to the rectangular forms 12 and 13.

The anodes 9 could be replaced by cylindrical anodes having apertures shaped like the anodes shown in Figure 14. In this case the apertured electrode would serve as the intercepting electrode, the apertures of course lying in the path of the beam from the cathode 2. It is also possible in the construction shown in Figure 10 to provide the electrode 10 with a surface which will promote secondary emission, the secondary 20 electrons returning to the anodes 9. If desired, the electrodes 9 could be replaced by intercepting electrodes made of gauze, properly treated to promote secondary emission for increasing the output to the electrode 10.

The intercepting electrode between the control grid 3 and the anode 4 may take the form of a screen grid having a specially shaped aperture for determining the shape of the characteristic curve. Figure 12 shows a screen grid with 30 an hour glass shaped aperture 15 covered by a wire mesh and by means of which in conjunction with the mount structure shown in Figure 10 a straight characteristic curve can be obtained. Figure 13 shows a screen grid in which the aperture 16 covered by a wire mesh and of the general shape of a double concave lens gives, in conjunction with the mount construction shown in Figure 10, an exponential type of grid voltage-plate current characteristic curve.

We claim:

1. An electron discharge device having an electrode system comprising a rectilinear cathode, an anode, a beam forming electrode adjacent said cathode and consisting of spaced conductors substantially parallel with the longitudinal axis of the cathode for concentrating the electron discharge from the cathode into a flattened radial beam with its width extending lengthwise of the cathode, an intercepting electrode adjacent said beam forming electrode and between said beam forming electrode and said anode, said intercepting electrode having in the path of the beam an aperture smaller than the normal cross-sectional area of the beam at said intercepting electrode, and means at the opposite ends of the electrode system for producing an electrostatic field to vary the width of the electron beam in a direction parallel with the longitudinal axis of the cathode.

2. A device as defined in claim 1 in which the cathode is indirectly heated and the means for producing an electrostatic field comprises end electrodes mounted at the ends of the electrode system and extending in a plane normal to the cathode and connected to the cathode.

3. An electron discharge device comprising an elongated cathode, a control grid comprising a pair of spaced conductors mounted parallel with and on opposite sides of said cathode to produce a sheet electron beam extending lengthwise of and radial to said cathode, end electrodes at opposite ends of said cathode extending normal to said cathode and to the plane of said rods, means electrically connecting said end electrodes to said control grid, an anode surrounding said

cathode and control grid, and an intercepting member between said anode and said control grid having intermediate its ends and in the path of said radial beam an aperture narrower than the 5 normal width of said beam in a direction parallel to said cathode.

4. An electron discharge device having an electrode system comprising a rectilinear cathode, a beam forming electrode adjacent said cathode 10 for concentrating the electron discharge from the cathode into a flattened radial beam with its width extending lengthwise of said cathode, two juxtaposed anodes of different diameters surrounding and coaxial with said cathode, the inner 15 5 one of said anodes having in the path of said electron beam an aperture with its width extending lengthwise of said cathode and less than the normal width of the beam at said inner anode, end electrodes mounted at opposite ends 20 of the electrode system and projecting in planes substantially normal to said cathode and along the edge of said electron beam on opposite sides of the aperture in said inner anode and means for connecting said end electrodes to said beam 25 forming electrode.

5. An electron discharge device comprising a rectilinear cathode, an anode surrounding said cathode, a beam forming electrode adjacent said cathode for concentrating the electron discharge 30 from said cathode to said anode into a flattened beam radial to said cathode and with its width

parallel to said cathode, end electrodes at opposite ends of said electrode system extending substantially perpendicular to said cathode and said beam forming electrode and parallel to the edges of the radial electron beam, means connecting said end electrodes to said beam forming electrode, and an intercepting electrode adjacent and on the cathode side of said anode and having in the path of said beam between said end members a grid-like aperture smaller than the 10 normal cross-sectional area of the beam at said intercepting electrode.

6. An electron discharge tube comprising an electrode system having an elongated indirectly heated cathode, an anode, a beam forming control electrode between said cathode and said anode consisting of two elongated spaced conductors parallel with and on opposite sides of the cathode to form the discharge from said cathode to said anode into a sheet beam radial to said 20 cathode and with its width parallel to said cathode, two end electrodes electrically connected to the control electrode inside the tube and mounted at the opposite ends of the electrode system to extend in planes normal to the cathode, 25 and an intercepting electrode between said beam forming electrode and said anode having in the path of said beam an aperture narrower than said beam.
